UNITED STATES PATENT OFFICE.

JOSEPH S. TARR, OF CLEVELAND, OHIO.

COMBINED CORN-SHELLER, FEED-GRINDER, AND HORSE-POWER.

SPECIFICATION forming part of Letters Patent No. 272,495, dated February 20, 1883.

Application filed November 27, 1882. (No model.)

To all whom it may concern:

Be it known that I, JOSEPH S. TARR, of Cleveland, in the county of Cuyahoga and State of Ohio, have invented certain new and useful Improvements in a Combined Corn-Shell-
er, Feed-Grinder, and Horse-Power; and I do hereby declare the following to be a full, clear, and exact description of the invention, such as will enable others skilled in the art to which it
pertains to make and use the same.

My invention relates to improvements in a combined corn-sheller, feed-grinder, and horse-power; and it consists of parts and combinations of parts, more fully hereinafter described
and claimed.

The object of my invention is to combine in one machine devices that have hitherto been usually separated, and to make said combined machine cheaper, and also more simple and compact in its construction, than machines of this class heretofore in use.

In the drawings, Figure 1 represents a side elevation view of the entire combined machine. Fig. 2 represents a top view of the same device. Fig. 3 is a vertical sectional view of the same as Fig. 1. Fig. 4 is a detailed plan view of one portion of the device shown in Fig. 3.

In Fig. 1, A represents a hollow supporting column, terminating in a broad base suitable for fastening to a foundation and supporting the entire machine. A short distance above the base of and inclosed in said column is placed the inclined disk a, terminating in the discharging-orifice a'. Directly over said disk is placed an inclined screen, b, terminating in a discharging-orifice, b'. Said screen is made detachable.

B represents a master-wheel, and is of that variety known as a "crown-wheel," and is attached firmly to the column A by means of a collar, A', and engages the pinion f. The said pinion and the spur-wheel F are attached to the shaft f'. The spur-wheel F engages the pinion g when in the position shown, but may be moved along the shaft f' so as to disengage the pinion g. The pinion g is attached to the shaft G, as are also the movable parts of the corn-sheller D and the feed-grinder E.

H represents a rotating collar, having for its bearing and axis the column A. To the said collar is attached the box h, the said box constituting the bearing for one end of the shaft

f', the other end of the shaft f' having its bearing in the box c.

C represents a rotating frame, one end of which is provided with a vertical cylindrical bore, C', having for its bearing and axis the column A. Said frame supports by one of its branches the box c, and supports also, by its other two branches, c' and c², the corn-sheller D. To the frame C is attached the arm c³, supporting the feed-grinder E. To the frame C is also attached the power-lever L, (shown more clearly in Fig. 4.) said lever moving in the direction of the arrow at l.

The said corn-sheller D consists externally of the cylindrical casing d, provided with the box d' and a hopper, d², into which the ears of corn are fed, and also provided with a discharging-orifice, d³. The said corn-sheller consists internally of the toothed cylinder I, attached to the shaft G. The said cylinder, acting upon the ears of corn, in connection with the inner surface of the said casing, rubs the grains of corn from the cob. The shelled corn and the cobs are discharged through the orifice d³ into the chamber of the column A and fall upon the screen b. When the cobs are arrested and discharged through the orifice b', the corn, passing through said screen upon the disk a, is discharged through the orifice a'. 65

The feed-grinder E consists externally of a casing provided with the receiving-hopper e, the discharging-orifice e', and has attached the box e², supporting one end of the shaft G. Internally the said grinder consists of two circular, serrated, grooved, plano-concaved grinding-plates, k and k'. The plate k' is attached by means of a flange and the pin j to the shaft G, and rotates with said shaft. The other plate, k, is attached to the side of the casing next to the hopper e, and through an annular opening in the center of the said plate k the grain passes from said hopper between the concaved grinding-surfaces of said plates. 70 75 80 85 90 95

The grain, when ground, is discharged through the orifice e' into the chamber of the column A, and, falling through the screen b and upon the disk a, is discharged through the orifice a'. 100

on the lever opposite said box, the torsional strain on said machine is reduced to a minimum.

The operation of my device is as follows: Power being applied to the lever L, the attached frame C is made to rotate around the column A. The said frame C, by means of the attached box e, carries with it in its rotations the shaft f', and by means of the engagement of the pinion f with the stationary wheel B the shaft f' is made to revolve on its own axis, and this last aforesaid rotary motion is conveyed by means of the engaging-wheels F and g to the shaft G and its attachments. The pin j may be withdrawn, leaving the grinder at rest while the corn-sheller is at work. The fly-wheel m and the pulley n are provided in case power by belt is desired to be applied to said shaft G. In that case the wheels F and g are disengaged, as aforesaid, by any desired means, and the frame C is fastened securely to the wheel B by means of the set-screw O.

What I claim is—

1. In a combined corn-sheller, feed-grinder, and horse-power, the combination, with a hollow column serving as a passage for the shelled corn or grain, of a master-wheel rigidly secured thereon, and shelling and grinding devices supported upon said column and provided with operating devices, substantially as set forth.
2. In a combined corn-sheller, feed-grinder, and horse-power, the combination, with a hollow supporting-column serving as a passage-chamber, and provided with a sieve and discharge-disk connecting with suitable discharge-orifices, of grinding and shelling mechanism supported upon said column and adapted to empty their contents into the latter, a master-wheel, and devices for operating the grinder and sheller, substantially as set forth.
3. In a combined corn-sheller and feed-grinder, the combination, with a hollow supporting-column serving also as a discharge-passage for the ground feed and shelled corn,

of a master-wheel secured upon said column, a rotating collar arranged upon the column, and a shaft carrying a bevel-gear wheel and a spur-wheel and adapted to operate the grinder and sheller, substantially as set forth. 45

4. In a combined feed-grinder and corn-sheller, the combination, with the hollow column, its master-wheel, and the rotating collar arranged on said column, of a rotating frame, a shaft, f, and connections for operating the grinder and sheller, substantially as set forth. 50

5. The combination, with a supporting-column, of a rotating collar arranged thereon, a frame supported upon said column and adapted to be revolved around the latter, and a corn-sheller, substantially as set forth. 55

6. The combination, with the supporting-column and collar H, of the frame C, adapted to be revolved around said column, and a feed-grinder supported above said column, substantially as set forth. 60

7. The combination, with the supporting-column and the collar H, of a frame, C, and a combined corn-sheller and feed-grinder constructed to rotate around the axis of said column, substantially as set forth. 65

8. The combination, with the column A and collar H, of the frame C, the pinion f, shaft f', and the wheel B, substantially as set forth. 70

9. The combination, with a hollow supporting-column and horse-power devices connected therewith, of a feed-grinder and corn-sheller arranged above said column and adapted to deliver their contents to the hollow column, which operates as a discharge-passage, substantially as set forth. 75

In testimony whereof I sign this specification, in the presence of two witnesses, this 3d day of November, 1882.

JOSEPH S. TARR.
